INVENTOR
William H. McCACKEN
BY
D. Anthony Lewis
ATTORNEY

UNITED STATES PATENT OFFICE.

WILLIAM H. McCACKEN, OF BIRMINGHAM, ALABAMA.

SOFT HAMMER.

Application filed March 21, 1928. Serial No. 263,496.

This invention relates to improvements in hammers provided with a relatively soft metal striking face so as not to mar or damage machined surfaces when making drive fits.

5 The hammer is also useful as a sledge buffer. That is, it may be used as an intermediate tool to be pounded by another hammer, the soft face of the improved hammer being held in contact with the work and a driving force 10 being transmitted through the tool steel head of the improved hammer. I am aware that heretofore hammer heads have been made entirely of copper, lead, and similar soft metals but when such hammers become marred they 15 are usually discarded in their entirety. Their use is, therefore, wasteful. Moreover, in service the heads of the former soft hammers easily work loose from the hammer handles. Such soft metal heads are not suitable for 20 use as buffers in connection with other sledges because they are so readily deformed or mashed to a form which renders them unsuitable for further use.

My improved hammer provides a tool having 25 a replaceable soft working face and overcomes the disadvantages inherent in the tools of this class heretofore used. The invention will be fully apparent from the following description when read in connection with 30 the accompanying drawings and will be defined with particularity in the appended claims. In the drawings—

Fig. 1 is a side view of a hammer embodying my invention;

35 Fig. 2 is a top view thereof with a portion of the hammer shown in section.

Referring in detail to the drawings, 10 represents a tool steel hammer head which is provided with the usual socket 12 for the reception of the hammer handle 14. To at 40 least one end of the hammer head, I provide a soft metal working face. In the embodiment of the invention illustrated, this working face is secured by brazing a copper piece 45 16 to the end of the hammer head, this piece 16 being provided with an integral tapered dowel portion 18 which engages a similarly tapered socket 20 formed in the end of the hammer head. The dowel portion 18 makes 50 a snug fit with the socket 20 and serves to center the piece 16 with the hammer head 10. The front of the hammer head is bevelled as

indicated at 21 so as to form an annular pocket or groove for the reception of the metal or alloy 22 which forms the bond or joint between the piece 16 and the end of the hammer head.

55 The joint may be conveniently made by means of an ordinary brazing alloy or the parts can be secured by an electric welding pencil or by oxyacetylene or other types of welding.

Because of the drive fit between the tapered dowel 18 and the similarly tapered socket 20 formed in the tool steel head, the joint 65 metal 22 is relieved of certain working strains, the dowel member especially taking the shear or side strains, thus helping to prevent the loosening of the copper piece 16.

From the foregoing it is apparent that 70 when the soft metal piece 16 becomes deformed or badly worn from use, it can be readily detached by chipping away the bonding metal 22 by means of a cold-chisel and hammer, thus the worn stump of the piece 75 16 can be knocked off and a new soft face applied and welded in position.

Various modifications may be made without departing from the invention as defined in the appended claims.

80 What I claim is:—

1. A hammer head of hard metal having a removable face piece of softer metal, said head and face piece being interlocked with one another to resist lateral strains and having substantial abutting surfaces to sustain the ordinary hammering strains normal to 85 said surfaces and a shallow external welded joint between the head and the removable face piece readily susceptible to intended destruction for removal of the soft metal face piece.

2. A hammer head of hard metal having a removable face piece of softer metal, said parts having substantial abutting faces to 95 sustain the ordinary strains of hammering normal to said faces and a shallow marginal welded joint between the head and the removable face piece readily susceptible to intended destruction for removal of the soft 100 metal face piece.

In witness whereof, I have hereunto signed my name.

WILLIAM H. McCACKEN.
